DEVICE FOR RAISING AND TIPPING CONTAINERS

Milton J. Christiansen, deceased, late of Brookfield, Ill., by
Blanche E. Christiansen, executrix, Brookfield, Ill., as
signer to Western Electric Company, Incorporated,
New York, N.Y., a corporation of New York

Filed Apr. 16, 1962, Ser. No. 189,226
3 Claims. (Cl. 214—313)

This invention relates to an apparatus for raising and tipping containers, and more particularly to a device for raising pans of piece parts from a lower level beneath a work bench to a level above the work bench and for tipping the pan to empty the contents thereof onto the bench.

An object of the invention is to provide an improved device for raising and tipping containers.

Another object of the invention is to provide an improved device for raising containers from a lower level below a work bench to an upper level above the work bench and for tipping the container to empty the contents thereof onto the work bench.

A device illustrating certain aspects of the invention may include an elevator carriage slidably supported on vertical guides of a fixed frame, and a drive mechanism for moving the carriage vertically from a normal lower position at a level beneath a work bench to a level above the work bench. A carrier for supporting a container of piece parts thereon is mounted on the carriage in a normal horizontal position for vertical movement with the carriage and for pivotal movement relative thereto about a horizontal axis. A gear fixedly secured to the carrier concentric with the axis is engageable with a rack bar mounted on one of the guide members in the path of upward movement of the gear and in a predetermined position above the gear when the carriage is in its normal lower position. In response to upward movement of the elevator carriage, the carrier and the container is moved upwardly therewith in horizontal position to a predetermined level above the work bench at which time the gear engages the stationary rack bar and imparts turning movement to the carrier and the container thereon to vertical position to cause the contents of the container to empty onto the bench.

Other objects, advantages and novel aspects of the invention will become apparent upon consideration of the following detailed description, in conjunction with the accompanying drawings, in which:

FIG. 1 is a fragmentary vertical longitudinal sectional view of the device for raising and tipping containers embodying the present invention;

FIG. 2 is a plan view of the raising and tipping device;

FIG. 3 is an enlarged fragmentary horizontal sectional view of the device taken on line 3—3 of FIG. 1;

FIG. 4 is a perspective view of the elevator carriage of the device showing a carrier pivotally supported on the carriage in an intermediate position; and

FIG. 5 is an enlarged fragmentary horizontal sectional view of the device taken on line 5—5 of FIG. 1.

The present device is designed to receive tote pans 15 of piece parts from a conveyor 16 at a predetermined level below a work bench 14 and to raise the pan of piece parts to a level above the work bench and then rotate the pan about a horizontal axis to a vertical position to effect the emptying of the piece parts from the pan onto the work bench 14.

Generally, the device comprises a stationary frame 20 mounted on a base 21 and including a plurality of vertically disposed tubular guides 22 for guiding an elevator carriage 24 for vertical movement. Mounted on the carriage 24 in a normal horizontal position is a carrier 26 for supporting the pan 15 of piece parts thereon for vertical movement with the elevator carriage 24. The carrier

2

26 is fixed to a shaft 28 which is journalled in the carriage 24 and supports the carrier for pivotal movement about the axis of the shaft. Two gears 29 are also fixed to the shaft 28 and are adapted to engage and mesh with the gear teeth of a pair of rack bars 30 secured to a pair of vertical guides 22 at a level spaced above the normal lower position of the carriage 24.

Vertical movement is imparted to the elevator carriage 24 by a drive mechanism 35 on the upper part of the frame 20. In response to the upward movement of the elevator carriage 24, the carrier 26 and the pan 15 of piece parts is raised therewith to a level above the work bench 14 during the latter portion of which movement the gears 28 mesh with the stationary racks 30 and cause the pivotal movement of the carrier 26 and the pan 15 to a vertical position to effect the emptying of the contents of the pan onto the work bench 14.

The vertically disposed tubular guides 22 of the frame 20 are secured to each other by suitable transverse frame members including upper and lower horizontally disposed frame plates 36 and 37, respectively, and a pair of vertical sides plates 38 at the upper portion of the frame. As shown particularly in FIG. 4, the elevator carriage 24 comprises four tubular elements or legs 40 slideable within the tubular guides 22 for vertical movement and connected to each other by a pair of side plates 42 and a transverse cross member 44. Longitudinally extending slots 45 (FIGS. 4 and 5) in the tubular guides 22 of the frame 20 provide clearance for movement of the side plates 42. Bearings 46 secured to the side plates 42 support the shaft 28. In its normal lower position the elevator carriage 24 is supported by the tubular legs 40 which rest on the lower horizontal frame plate 37.

The carrier 26 includes a pair of side frames 47 of L-shaped cross section secured together in spaced relation to each other by a pair of cross members 48 and having at one end a pair of blocks 49 for receiving the shaft 28 therein. The shaft 28 is fixedly secured to the blocks 49 and to the gears 29. Extending between the side frames 47 and rotatably supported thereby is a row of rollers 50 which serve as a platform for supporting the pan 15 of piece parts thereon. At one end of the carrier 26, adjacent to the shaft 28, a vertically disposed plate 51 is secured to and extends between the side frames 47. As shown in FIG. 1, the side frames 47 and the end plate 51 extend upwardly above the upper surface of the rollers 50 to retain the pan 15 on the carrier during the tilting movement of the carrier 26.

Supported on the upper end of the frame 20 is a drive mechanism 54 for raising and lowering the elevator carriage. The drive mechanism includes a plurality of chains 55 which extend within the tubular guides 22 and are secured to the upper ends of the tubular members 40 of the carriage. The upper portions of the chains 55 pass around idler sprockets 56 suitably supported on the upper ends of the tubular guides 22 and are secured to a pair of sprocket wheels 57, with a pair of the chains secured to each sprocket in diametrically opposed relation to one another. The sprocket wheels 57 are secured to a shaft 58 which is supported at opposite ends in bearings 59 on the vertical side plates 38 of the frame 20. Rotation is imparted to the shaft 58 by a reversible motor 62 which is operatively connected to the shaft 58 through a speed reducing transmission 63 and is connected to a source of electrical power through a control switch (not shown).

In the operation of the device with the elevator carriage 24 in its normal lower position, a pan 15 of piece parts is manually transferred from the horizontal conveyor 16 onto the rollers 50 of the carrier 26 and the control switch is operated to actuate the motor 62 in one direction. This causes the sprocket wheels 57 to wind thereon portions of the chains 55 and effect the upward

movement of the elevator carriage 24 to a predetermined upper position at which point a switch 65 (FIG. 2) is actuated by a cam 66 on the shaft 58 to stop the motor 62.

As the carriage 24 moves upwardly, the carrier 26 and the pan 15 are moved upwardly therewith in horizontal position to a predetermined elevation in the region of the bench 14 at which time the gears 29 on the carrier 26 mesh with the rack bars 30 and are rotated thereby as the carriage continues its upward movement thereby turning the carrier 26 and the pan 15 about the axis of the shaft 28 to a vertical position and causing the piece parts to be discharged from the pan 15 onto the work bench 14. A U-shaped strap 68 (FIG. 2) is secured to the upper portion of the frame 20 above the bench 14 in a position to prevent the pan 15 from turning too far and tipping over onto the work bench 14.

After the piece parts are removed from the pan 15, the manually operated motor control switch is operated to actuate the motor 62 in the reverse direction and effect the return movement of the elevator carriage 24 to its lower position. During the initial portion of the downward movement of the elevator carriage the carrier 26 is returned from the vertical to a horizontal position as the gears 29 are rotated by the rack bars 30. As the carrier 26 turns about the shaft 28, the pan 15 is manually held thereagainst until the carrier has turned sufficiently from the vertical position to support the pan thereon. If desired, a latch may be provided on the carrier to releasably hold the pan onto the carrier during return movement from tilted to horizontal position.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. A device for emptying the contents of containers onto a work bench comprising a stationary frame positioned adjacent to the work bench and including a lower base member, an upper horizontal frame member, and four vertically disposed tubular guides extending between said base and said upper frame members at the corners thereof with each of said tubular guides having a longitudinal slot therein; an elevator carriage including tubular elements slideable within said tubular guides, a pair of parallel side plates, each of said side plates interconnecting a pair of said tubular elements and extending through the slots in said tubular guides, a cross member interconnecting said pair of side plates adjacent to one pair of said tubular guides, and a shaft extending transversely of and journaled in said side plates adjacent to the other pair of tubular guides; a carrier fixedly connected at one end thereof to said shaft and supported by said shaft and said cross member in a normal horizontal position on said carriage, said carrier including a pair of side members parallel to said side plates of said carriage, a plurality of rollers extending transversely between and rotatably supported on said side members in a horizontal row for supporting a container thereon, an end plate extending transversely between said side members adjacent to said shaft and extending upwardly above the upper surface of the row of rollers for limiting the movement of the container on said carrier in one direction, and a pair of gears fixedly connected to said shaft; a pair of rack bars mounted on a pair of said tubular guides above and in the path of movement of said gears with said carriage in a lower position; chains connected to said tubular elements and extending upwardly therefrom within said tubular guides; and selectively operable means mounted on said upper horizontal frame plate for actuating said chains to raise and lower said carriage to and from a nor-

mal lower position at a level below the work bench and an upper position above said work bench; the arrangement being such that during the latter portion of the upward movement of said carriage said gears engage and are actuated by said rack bars to effect the turning of said carrier and the container thereon from a horizontal to a tilted position.

2. A device for emptying the contents of containers onto a work bench comprising a stationary frame positioned adjacent to the work bench and including a lower rectangular base member, an upper horizontal frame member, and four vertically disposed tubular guides extending between said base and said upper frame member at the corners thereof with each of said tubular guides having a longitudinal slot therein; an elevator carriage slidably mounted on said tubular guides and including slide elements slideable within said tubular guides, a pair of parallel side plates, each of said side plates interconnecting a pair of said slide elements and extending through the slots in said tubular guides, a cross member interconnecting said pair of side plates adjacent to one pair of said tubular guides, and a shaft extending transversely of and journaled in said side plates adjacent to the other pair of tubular guides; a carrier fixedly connected at one end thereof to said shaft and supported by said shaft and said cross member on said carriage in a normal horizontal position, said carrier including a pair of side members disposed parallel to the side plates of said carriage, a plurality of rollers extending transversely between and rotatably supported on said side members in a horizontal row for supporting a container thereon, an end plate extending transversely between said side members adjacent to said shaft and extending upwardly above the upper surface of said rollers for limiting the movement of the container on said carriage in one direction, and a pair of gears fixedly connected to said shaft; a pair of rack bars mounted on a pair of said tubular guides above and in the path of movement of said gears when the carriage is in a lower position; a pair of sprockets rotatably supported on said upper frame; chains individual to said slide elements connected at one end to said elements and connected at the other end to said sprockets in pairs and in diametrically opposed relation to one another; means for guiding said chains upwardly through said tubular guides and onto said sprockets; and selectively operable drive means including a reversible motor supported on said upper frame plate for rotating said sprockets; the arrangement being such that during the latter portion of the upward movement of said carriage said gears engage and are rotated by said rack bars to effect the turning of said carrier and the container thereon from a horizontal to a vertical position.

3. An elevating and tipping device comprising a frame means including a base and four tubular guides each extending upwardly from said base and having a longitudinal slot therein; an elevator carriage including elements slideable within said tubular guides and normally resting on said base for supporting said carriage, a pair of parallel side plates each interconnecting a pair of said elements and extending through the slots in said tubular guides, a cross member interconnecting said pair of side plates adjacent to a pair of said tubular guides, and a shaft extending transversely of and journaled in said side plates adjacent to the other pair of said tubular guides; a carrier supported on said shaft for pivotal movement about the axis thereof and supported by said shaft and said cross member in a normal horizontal position on said carriage for supporting a container thereon, a gear mounted on said shaft in fixed relation to said carrier for pivotal movement therewith; a rack bar fixedly mounted on one of said tubular guides above and in the path of movement of said gear when said carriage is in a normal lower position with said elements resting on said

base, chains connected to said elements and extending upwardly therefrom, and means for actuating said chains to raise said carriage from the normal lower position to a predetermined upper position to cause the carrier to be raised in a horizontal position for a predetermined distance and to cause the gear to engage said rack and to effect the rotation of the carrier to a tilted position.
